UNITED STATES PATENT OFFICE

JAMES BOYCE, OF LAKETOWN TOWNSHIP, ALLEGAN COUNTY, MICHIGAN, AND
RAYMOND F. HANCOCK, OF MARION, INDIANA, ASSIGNORS TO CHICAGO GLASS
MOBILITY CORPORATION

• SIGN

Application filed June 24, 1929. Serial No. 373,087.

The invention relates generally to illuminated signs and more particularly to individually formed sign units or letters of the kind ordinarily used in the interiorly illuminated box type of sign.

The present invention has for its primary object the provision of a glass sign letter or unit for box type signs which may be manufactured by the same economical production methods heretofore used and having such a form and being of such a material that by mounting it in different ways or employing various simple methods of decoration and illumination, a highly efficient sign may be produced in which each character is composed of any desired one of a large variety of vivid colors or combinations of contrasting colors so as to provide an unusually attractive sign for both day and night display.

A further object is to provide such a sign unit in which a part of the character stroke is illuminated by a brilliant light capable of catching the eye of an observer in a degree comparable to the light given off by a luminescent-tube sign.

It has been found that the glaring character of the light given off by luminescent tube signs is very effective in attracting the attention of an observer, but this very characteristic results in definitely limiting the range of distance over which the observer may actually read the characters of the sign. Thus at close ranges the excessive brightness of the tubes tends to strain the eyes of the observer and thus discourage reading of the sign, while at great distances the character strokes merge with each other and the sign becomes a blurred mass of color so as to be ineffective to convey advertising thoughts or words to the mind of the observer.

It is also well known that signs formed of luminescent tubes alone present a very unsatisfactory appearance when displayed in the day time without illumination since

the blackened portions of the tubes tend to distract the observer's attention from the advertising character which the sign is intended to impress upon the observer.

Another object of the invention is to provide a sign arranged to give off a light of a character similar to that given off by a luminescent tube sign, the sign being of such a construction that the characters or letters are readily readable at practically all ranges and present a finished, pleasing, and legible appearance when displayed in the day time without illumination. 50 55

Because of the many varying factors which affect the advertising efficiency of luminescent tube signs and also because of the many limitations and difficulties involved in their manufacture, it has been found that such signs must be designed by highly skilled men, and since each different sign presents different problems the high labor cost of such designers enters into and forms a very considerable portion of the ultimate cost of each sign. In addition to this, the tubes must be bent to form by skilled glass blowers, thus adding another material item to the cost of each sign. Such signs are operable only by alternating current of very high voltage and since such current is not provided in most localities, it is usually necessary to install suitable transformers and converters and in addition to the initial cost of such equipment, the user must bear the losses due to the low efficiency of operation of the equipment. Moreover, the cost of maintenance of such signs is very considerable.

A further object is to provide a sign capable of being efficiently illuminated by the use of either alternating or direct current of normal voltage and arranged so as to present an unusually attractive, pleasing and legible appearance when used in the day time without illumination so as to further reduce the cost of operation. 85

Luminescent tube signs are limited to a 90°

very few colors and it is another object of the invention to provide a sign arranged to give off a light of a similar brilliant and attractive character, in which sign many different colors and shades of colors may be economically provided.

Another object is to provide a sign having many of the advantages of a luminescent tube sign without the high cost of maintenance.

The above and other objects are attained through the provision of a sign unit adapted to be mounted in the conventional manner in the side of an internally illuminated box type of sign and formed from a crystal (i. e. transparent) glass plate to produce a composite sign character giving the effect of two or more distinct characters and made up of two or more parallel superposed character strokes all of which are raised with respect to the plate and have comparatively thin walls and the lower stroke or strokes being of lens-like form, the outer or upper strokes being progressively narrower so as to be flanked or bordered on both sides by the lower character strokes.

Other objects and advantages will become apparent from the following description taken in connection with the accompanying drawings in which:

Fig. 1 is a front elevational view of a sign letter embodying the preferred form of the invention.

Fig. 2 is a front elevational view of a sign letter embodying an alternative form of the invention.

Fig. 3 is an enlarged cross sectional view of the letter shown in Fig. 1 taken along the line 3—3 of Fig. 1.

Fig. 4 is a sectional view through a second alternative construction.

Fig. 5 is a sectional view taken along the line 5—5 of Fig. 2.

Fig. 6 is a front elevational view of another alternative form.

Fig. 7 is an enlarged sectional view taken along the line 7—7 of Fig. 6.

Fig. 8 is a front elevational view of a letter embodying the invention.

Fig. 9 is a cross sectional view taken along the line 9—9 of Fig. 8.

Fig. 10 is a front elevational view of a sign letter embodying the invention.

Fig. 11 is a sectional view taken along the line 11—11 of Fig. 10 showing a colored glass plate used for obtaining various color effects in the letter.

While we have shown in the accompanying drawings and will herein describe in detail the preferred embodiment of the invention together with several alternative embodiments thereof, it is to be understood that this disclosure is given for the purpose of illustrating the invention and the many varied sign effects obtainable thereby and is not

intended as a limitation of the invention to the constructions disclosed. In the appended claims, we aim to cover all modifications and alternative constructions falling within the scope of the invention.

In the drawings the invention is illustrated as embodied in a single character sign unit consisting of a glass plate or panel 14 embossed or raised at 15 to form the desired letter or character. In order that the sign may be easily decorated to provide color contrast throughout the entire length of the letter outline, the embossed portion 15 is formed to provide a plurality of distinguished similarly shaped letters of varying sizes each projecting forwardly with respect to the plate and having comparatively thin side walls, the smaller letters being superimposed upon the larger letters so that the larger letters support smaller ones and form, in effect, a border therefor.

In signs of this character it is desirable for the sake of economy to minimize the loss of light intensity and for this reason the sign letter is formed from crystal (i. e. transparent uncolored) glass. The decoration of the sign letter may be most easily made on the inner surface thereof and when so made, the effective or visible surface of the paint is protected against weather and dirt and is visible through the crystal glass walls of the embossed portion 15 and renders the sign attractive when displayed during the day.

In the embodiments illustrated in Figs. 1, 3, 4, and 8 to 11, the embossed portion 15 is shaped to produce two distinct similar letters superposed one upon the other. The cross-sectional form of the two letters thus provided may be varied considerably as will be apparent from a comparison of Figs. 3 and 4. In the form shown in Figs. 1 and 3, the outer or foremost letter consists of an outwardly convexed portion or character stroke 16 superposed upon and supported forwardly of the plate by the second and larger letter which is formed by outwardly extending border portions 17 disposed along the sides of the central character stroke 16 and formed integrally with the stroke 16 and the plate 14.

The border portions 17 extend outwardly from the plate 14 at an obtuse angle relatively to the plate to the point 18 where they join the central portion 16 so that they are clearly visible from the front as well as from the side of the sign unit.

As above pointed out, the sign unit is preferably formed from crystal glass so that the light is transmitted through the border portions 17 without material loss of intensity or brilliancy, and to increase the effectiveness of the sign the border portions 17 which form the larger or lower letter are preferably lens-like in character so as to diffuse the light rays emanating from the source and

produce an apparent magnification of the light source. It will be noted that the border portion 17 is of less thickness than the plate 14 and becomes gradually thinner toward the point 18 where it joins the central portion 16 so that the resulting refraction of the light rays will be different in the different parts of the border, thus producing a diffusion of the light.

10 In the form shown in Figs. 4 and 8 to 11, the border portions 17^a are in the form of concavo-convex lenses, while in the form shown in Figs. 1 and 4, the lens is formed in part by the angular relation of the inner and outer faces of the border portions 13 to each other. As shown in Fig. 3, the border portion 17 comprises a substantially straight section 20 which varies in thickness so as to diffuse the light passing therethrough and is joined at its outer end to the edge of the central portion 16 by a rounded rib 21 which varies in thickness and has a greater lens effect than the straight section 20.

15 In Figs. 2 and 5 another alternative construction of the sign unit is shown having a similar plate 14^b and an embossment 15^b thereon, the border portions 17^b being formed by three ribs 22 of a character similar to the ribs 21 shown in Fig. 3 but of less width. Since the borders 17, 17^a, and 17^b in each form are lens-like in character and are positioned at an obtuse angle to the base plate, an observer will see a diffused light whether the sign is viewed from the front or the side thereof.

20 When the unit is positioned in a suitable internally illuminated box-like casing (not shown) the outer edge of the border portions 17 may be clearly defined by rendering the plate 14 opaque by means of a coating of paint constituting virtually a stencil, as shown at 24 in Figs. 1, 6, 8, and 10, or a sheet metal stencil 25 may be positioned over the plate 14 as in Fig. 3 and extending into abutment with the outer sides of the border portions 17.

25 It will be readily seen that the sign unit above described possesses all of the advantages inherent in the units heretofore used in box type signs and hence may be cheaply produced and mounted and the complete sign easily and economically installed, maintained and operated. The particular form of sign unit also results in a letter which may be produced on a quantity basis and by various simple expedients in mounting and decorating may be made to serve as a basis for the production of a wide variety of signs of differing appearance.

30 The importance of such a widely adaptable sign unit will be apparent when considered from the standpoint of the retail or wholesale sign maker who buys the sign units from the manufacturers and assembles them to produce the desired word combinations.

By keeping a stock of letters made in accordance with the present invention, such sign makers may provide their customers with a large selection of collar combinations without the necessity of having a complete assortment of a large number of kinds of different appearing sign units. This advantage also accrues to the manufacturer and the cost of production of the units may be reduced due to the fact that only one type of unit must be made.

35 Among the various combinations or sign effects attainable by the use of the sign unit herein disclosed, is a sign having the striking appearance, when illuminated, of a double tube neon sign. This result is attributable, in part, to the brilliant character of the light transmitted by the border portions 17 and in part to the particular formation and decoration of the central character stroke 16. Thus as illustrated in Figs. 1 to 5, the inner surface of the central character stroke 16 is coated as at 26 with opaque paint so that the two brilliant bands of light which pass through the two borders 17 and appear to come from a concentrated source will be separated by an intensely dark or unlighted strip. To render this dark central strip more pronounced or effective, the central portion 16 is made to project forwardly for such a distance that the light rays passing through the two border portions 17 can not cross each other. Thus a definite separation of the light from the two borders is effected.

40 The embossing of the character stroke 16 is preferably considerably higher than in the prior-art opal glass sign letters, and this in conjunction with the two brilliant borders of light causes the letter to appear to project or jut forwardly from the plate in much more pronounced manner than in the prior art signs.

45 By providing a colored light source within the sign the border portions 17 may be made to appear of any desired color or shade of color and it will be seen that by this arrangement the sign is capable of providing for economically varying the light effects so as to increase the effectiveness of the sign as an advertising medium. The colored light source may be provided in many different ways such as by the use of a neon tube mounted within the box, or by colored globes (not shown), or by the ordinary globes and a color filter such as a colored glass plate 28 (Fig. 11) mounted behind the sign unit.

50 While the construction provides for brilliantly illuminated borders on the sign characters, this does not prevent reading of the sign at close range since the central portions 16 project forwardly of the lenses and are of a contrasting color so that the sign character is quickly perceptible to the eye.

55 The sign unit above described is unusually effective as a night sign due to the fact that

it can be read from a comparatively great distance because of the definite separation of the luminous borders or margins of the character strokes, and it has been found that 5 the two borders of a four-inch sign letter are distinctly defined and the sign clearly readable at a distance upwards of one hundred fifty feet. The glowing borders have also 10 been found to produce an apparent increase in the size of the letter as compared with prior art letters of the same dimensions.

In the form shown in Figs. 1 to 5, the central strokes 16 of the letter are rendered opaque by means of a lustrous black paint as 15 indicated by the shading in Figs. 1 and 2 so that when the sign is displayed in the daytime without illumination, the central stroke will stand out clearly and present an easily 20 readable and attractive letter surrounded by light-reflecting colorless borders. If desired, the opaque coating of the interior of the character stroke 16 may be formed from bright colored paint to enhance its attractiveness. By using various colors of opaque 25 paint, the sign maker may provide an extremely large variety of attractive color combinations forming effective signs for daytime display, and all the signs thus produced are unusually effective as illuminated signs 30 due to the bright light given off by the lens-like borders.

The sign unit may also be used to produce a sign letter having parallel strokes of contrasting colors when displayed either at night 35 with interior illumination or during the daytime without illumination. Such a sign letter may be formed as shown in Figs. 8 and 9 by covering the inner surface of the central character stroke 16 with a coat 29 of 40 translucent colored paint. Such a coating provides an attractive contrast to the crystal glass borders 17^a when the sign is displayed during the day and is also effective at night 45 as a color screen to filter the light rays falling upon the inner surface of the stroke 16.

When a light source of a color brighter than the colored coating 29 is provided, the letter will, when illuminated, present an extremely attractive sign. Thus when the character stroke 16 is coated with a translucent red paint as indicated in Figs. 8 and 9, an amber colored light source may be used. Such a light source may be formed by globes 55 giving off a white light and an amber colored glass plate 30 positioned behind the letter in the manner illustrated in Fig. 9.

It has been found that a very interesting and attractive light effect may be obtained 60 in such cases by using a glass plate 30^a having a rough surface 31^b so that the light passing therethrough is concentrated in certain spots to give an uneven or speckled appearance to the translucent letter formed by the colored 65 central character stroke 16.

Another strikingly different sign may be produced from the same sign unit by coloring the interior of the character stroke as at 31 (Fig. 11) with transparent colored paint, the letter shown in Fig. 10 being shaded to 70 indicate transparent red paint. A white or colored light source may be employed with such a letter. If a colored light source is used, the central stroke 16 is of a contrasting color and both the stroke 16 and the borders 75 17^a give off a comparatively strong light to attract the attention of an observer.

A modified construction which provides an extremely attractive sign when transparent coloring is used, is shown in Figs. 6 and 7. 80 In this construction the embossed character stroke is formed from a series of steps or ribs 32 similar to the ribs 21 shown in Fig. 3. The series of ribs 32 forming the two side walls of the character strokes are stepped inwardly and are joined at their outer ends by a portion 33 parallel to the plate 14. The inner and outer surfaces of each rib 32 are at an angle to each other so that each rib constitutes a lens and modifies the light given off by the 85 sign so as to increase its effectiveness as pointed out in connection with the discussion of the letters shown in Figs. 1 to 5.

In the embodiment shown in Figs. 6 and 7, 90 five ribs 32 are provided and the outer two ribs and the connecting portion 33 are preferably colored as at 34 on their inner surfaces to form a sign letter which is definitely distinguishable and contrasts with the border formed by the other ribs 32. Figs. 6 and 7 95 are shaded to indicate transparent red coloring. Either a white or a colored light source may be used. When a colored light source of a different color is provided, the letter will have an illuminated central character stroke 100 of red with a border of contrasting color. 105

It will be readily seen that when the central character stroke is provided in the form shown in Figs. 6 and 7, the letter may be used equally as well as the letters shown in Figs. 1 to 5 and 8 to 11 for the production of the various sign combinations described in connection with those figures.

The form of letter shown in Figs. 6 and 7 110 does, however, possess an additional advantage when the central character stroke is colored by means of a transparent or translucent coating, since the light given off by the central stroke has a definite variation in intensity due to the fact that the stroke is formed from two of the ribs 32 and the connecting portion 33. Thus the connecting portion 33 appears to be of a comparatively light color surrounded by a darker band of colored light which is in turn surrounded by a lighter band and then another dark band of colored light. Such a contrast of the intensity of the color obviously increases the attractiveness of the letter. It will be noted 115 that this variation in intensity results from 120 125 130

the conformation of the letter and does not require additional care in decorating the letter. A similar variation in light intensity will also be apparent in the contrasting borders formed by the other ribs 32, this contrast being noticeable with either a white or colored light source.

Sign letters of the form herein shown are particularly adapted for the production of shaded letters since shading may be easily obtained by eliminating portions of the lighted borders. This may be done by modifying the construction of the letter or by merely painting the desired portions of the borders with opaque paint.

In such cases, the opaque paint used to mask certain portions of the borders may be of a bright color so that it will contrast with the color of the central character stroke 16 when the sign is displayed in the daytime. In case the attractiveness of the sign during the daytime is of primary importance, the borders may be coated with transparent paint of a color which contrasts with color of the central character stroke.

It should be observed that in each type of letter herein shown, the side walls of the embossed portion are of such a form as to facilitate decoration of the walls to provide contrasting parallel character strokes. Thus in Figs. 3, 4, and 8 to 11, the inner surface of the border 17 meets the inner surface of the central character stroke 16 at the point 18 so as to define a line of separation therebetween. With this construction, a paint brush may be drawn rapidly along the inner surface of the central character stroke 16 without danger of coloring the borders 17 which form the other character stroke.

Similarly in the form shown in Figs. 6 and 7, the inner surfaces of the ribs 32 meet each other at an angle so that the inner surface of selected ones of said ribs may readily be colored. With each form of sign above described the borders may be illuminated by white light or by any one of a large variety of colored lights while a correspondingly great variation may be obtained in the central stroke by the use of different shades and colors of transparent or translucent paints.

From the foregoing it will be apparent that the invention provides a sign unit which is readily adaptable for the production of a large variety of different appearing signs so as to render it unnecessary for a sign maker to keep on hand a large variety of different kinds of sign units. Furthermore, all of the different sign combinations obtainable by the use of the present sign unit are attractive and efficient either as day or night signs and may be operated and maintained economically.

We claim as our invention:—

1. A sign unit comprising a base plate formed from transparent glass and a com-

posite sign character embossed thereon from the material of said plate to give the effect of a plurality of distinct characters of different sizes superposed one upon the other, said composite character comprising, in cross section, an outwardly convexed thin-walled central character stroke positioned forwardly of and opening rearwardly with respect to said plate, and a second character stroke wider than said first stroke and having a portion positioned on each side of said central stroke so as to form a uniform raised border therefor, said portions being formed to provide a lens effect, and a coating of colored paint on the inner side of said central stroke.

2. A sign unit comprising a base plate formed from transparent glass, and a composite sign character embossed thereon, said character being composed of two parallel character strokes superposed one upon the other and both positioned forwardly of said plate, the walls forming both of said character strokes being of less thickness than said plate and the walls of one stroke being of varying thickness to provide lenses extending longitudinally of the character strokes.

3. A sign unit comprising a base plate formed from transparent glass and a composite raised sign character thereon to give the effect of a plurality of distinct characters of different sizes superposed one upon the other, said composite character comprising, in cross section, an outwardly projecting thin-walled character stroke having inner surfaces meeting at an angle at a point intermediate the plate and the outermost extremity of the stroke to provide a definite line extending longitudinally of the composite stroke to facilitate decoration of a definite portion of said stroke, and a coating of paint applied to a definite longitudinally extending portion of the inner side of said stroke, said portion extending laterally to the line defined by the intersection of said angularly disposed inner surfaces.

4. A sign unit comprising a base plate of glass having a raised character stroke thereon and projecting forwardly therefrom, said stroke having in cross section an outwardly convexed central portion positioned a substantial distance forwardly of the base plate, and a light-transmitting border portion at each side of said central portion connected to said plate and central portion and positioned at an obtuse angle to said plate, said central portion being opaque and projecting forwardly for a sufficient distance to prevent intermingling of the light transmitted through the two border portions.

5. A sign unit comprising a base plate of glass having an embossed character stroke formed thereon and projecting forwardly therefrom, said stroke having in cross-section an opaque outwardly convexed central

portion positioned forwardly of the plate, and a lens-shaped border portion on each side of and supporting said central portion in its forward position, said convexed central portion extending forwardly for a sufficient distance to definitely separate the light rays passing through said border portions.

6. A sign unit of the character described comprising a plate of glass having a character stroke embossed on its forward face, said stroke having, in cross section, an opaque outwardly convexed central portion and transparent border portions connecting said plate and central portion and supporting said central portion forwardly of said plate, said border portions being of gradually decreasing thickness as they extend away from said plate.

7. A sign unit of the character described comprising a plate of glass having a raised character stroke pressed outwardly therefrom, said stroke having, in cross section, an outwardly convexed opaque central portion positioned forwardly of said plate and lens-like transparent border portions joining the plate and the edges of the convex central portion, each border portion comprising a straight section extending outwardly from said plate at an obtuse angle thereto and being of gradually decreasing thickness towards its outer edge, and the outer edge of said section being curved to a position substantially parallel to said plate and then joined with the edge of said central portion.

8. In testimony whereof we have hereunto affixed our signatures:
